CLAIM

The ornamental design for combined keyswitch and joystick for a computer keyboard, as shown and described.

DESCRIPTION

FIG. 1 is a perspective view of combined keyswitch and joystick for a computer keyboard showing my new design on an enlarged scale;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a perspective view thereof, on a reduced scale, the broken line drawing of a keyboard is for illustrative purposes only and forms no part of the claimed design.
